US00D800721S

(12) **United States Design Patent** (10) **Patent No.:** **US D800,721 S**
(45) **Date of Patent:** **** Oct. 24, 2017**

(54) **WEARABLE ELECTRONIC DEVICE**

(71) Applicant: **SAMSUNG ELECTRONICS CO., LTD.**, Suwon-si (KR)

(72) Inventors: **Myung-Kyu Kim**, Seoul (KR); **Yong-Seok Bang**, Yongin-si (KR)

(73) Assignee: **SAMSUNG ELECTRONICS CO., LTD.**, Gyeonggi-Do (KR)

(**) Term: **15 Years**

(21) Appl. No.: **29/558,320**

(22) Filed: **Mar. 16, 2016**

(30) **Foreign Application Priority Data**

Nov. 27, 2015 (KR) 30-2015-0060249

(51) **LOC (10) Cl.** **14-02**

(52) **U.S. Cl.**

USPC **D14/344**

(58) **Field of Classification Search**

(57) **CLAIM**

The ornamental design for a wearable electronic device, as shown and described.

DESCRIPTION

FIG. 1 is a front perspective view of a wearable electronic device, showing our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is another perspective view thereof as shown in a band environment; and,

FIG. 10 is another perspective view thereof as shown in a ring environment.

The broken lines illustrating portions of the wearable electronic device form no part of the claimed design.

1 Claim, 8 Drawing Sheets
